UNITED STATES PATENT OFFICE

RAGNAR CLASON, OF FLINT, MICHIGAN, ASSIGNOR TO A C SPARK PLUG COMPANY, OF FLINT, MICHIGAN, A COMPANY OF MICHIGAN

CRANK-CASE VENTILATION

Application filed October 29, 1927. Serial No. 229,687.

This invention relates to crankcase ventilation for an internal combustion engine and is particularly adapted to use in an internal combustion engine of an automotive vehicle.

5 It is an object of the invention to provide a new and improved means for regulating the ventilating current of air passed through the engine crankcase during operation of the engine. More specifically it is an object of the 10 invention to provide a ventilating system operated by the suction of the air intake with means for maintaining the current of air through the crankcase substantially constant at any speed of the engine or for reducing the 15 current during high speed when the crankcase oil is heated and the diluents are readily volatilized.

Other objects and advantages of the invention will appear in the course of the following description, taken in connection with the accompanying drawing and appended 20 claims.

In the drawing:

Fig. 1 is a plan view partly broken away 25 of a conventional internal combustion engine embodying my invention.

Fig. 2 is a side elevation.

Fig. 3 is a side view of a modified form of 30 my invention.

Fig. 4 is an enlarged sectional view of the valve device shown in Fig. 3.

Referring to Figs. 1 and 2, I have illustrated a conventional internal combustion engine comprising an engine block 10, crankcase 12, intake manifold 14, and carbureter 16. 17 indicates the engine valve compartment located at one side of the cylinders which are indicated by the dotted circles in Figure 1. The valve chamber is closed by 40 means of the usual removable cover 19. On the cover 19 is mounted a cover 18, which together with the cover 19 forms an air chamber. A pipe 20 fitted in an aperture in the cover 19 establishes communication between 45 the air chamber and the valve compartment. A baffle 21 is secured to the cover 19, and extends over the pipe 20 to shield it against the entrance of oil. A conventional air cleaner 22 is fixed in an opening in the cover 18, and 50 fixed to the inner side of the cover 18 as by

rivets 24 is a flap valve 26. The valve is of spring material and normally covers the inner opening of the air cleaner but is adapted to swing inward to nearly close the pipe 20, the outer end of the pipe 20 being sheared at 55 an angle to coincide with the inner position of the valve 26, as shown in Fig. 1.

At the opposite end of the air chamber is connected a pipe 30 leading to the carbureter. At the front end of the engine I have provided 60 a conventional breather pipe 32 opening into the crankcase.

When the engine is running at low speed, there is but a slight vacuum within the air chamber and all the air drawn to the manifold 65 through the pipe 30 comes from the crankcase. As the speed of the engine increases, the vacuum in the air chamber increases and the flap valve 26 starts to open, admitting air through 70 the cleaner 22. As the speed of the engine continues to increase the valve 26 opens wider and almost but not quite completely 75 shuts off the current through the pipe 20. As the speed of the engine decreases, the action of the valve is just the reverse of that described. The valve thus acts as a damper for the ventilating device and insures that the current through the crankcase will not become great enough to draw out fine particles 80 of oil into the air chamber, as would be the case if the current through the crankcase increased directly with the speed of the engine.

In the modification shown in Figs. 3 and 4 the air chamber is provided by a casing 40 85 rigidly fixed on the forward side of the carbureter 16 and connecting therewith and provided with an opening on its forward side in which is fixed an air cleaner 42. A spring flap valve 44 similar to that above described 90 is riveted to the forward side of the casing 40 so that it normally closes the air cleaner opening but may swing open to the dotted line position illustrated in Fig. 4 to nearly close the end of the pipe 46 which leads to the 95 crankcase above the level of the oil. The operation of this form of my invention is similar to that described above. While it is convenient to provide an air chamber as illustrated, I desire it to be clearly understood that 100

the air chamber itself is not absolutely necessary and that it is necessary only that there be a connection between the air intake and crankcase sufficiently large to mount therein the compensating valve described.

5 I claim:

1. An engine having a crankcase, means for admitting air to the crankcase, said crankcase being provided with an air outlet port, a suction connection communicating with said outlet port, a port opened to the atmosphere communicating with said suction connection, and means cooperating with both of said ports and normally closing 10 one of said ports, said means being movable to vary the opening or closing of the ports.

2. An engine having a crankcase, means for admitting air to the crankcase, said crankcase being provided with an air outlet port, a suction connection communicating with said outlet port, a port open to the atmosphere communicating with said suction connection, and suction operated means cooperating with said ports and normally 20 closing the last port and being adapted upon application of suction to gradually open said last named port and close said first named port.

3. An engine having a crankcase, means 30 for admitting air to the crankcase, said crankcase being provided with an air outlet port, a suction connection communicating with said outlet port, a port open to the atmosphere communicating with said suction connection, and a valve overlying both of 35 said ports and movable to open one port and close the other.

4. An engine having a crankcase, means for admitting air to the crankcase, said 40 crankcase being provided with an air outlet port, a suction connection communicating with said outlet port, a port open to the atmosphere communicating with said suction connection, and a suction operated valve extending between and overlying said ports, 45 said valve being spring tensioned to normally close said atmospheric port.

5. An engine having a crankcase, means for admitting air to the crankcase, said 50 crankcase being provided with an air outlet port, a suction connection communicating with said outlet port, a port open to the atmosphere communicating with said suction connection, and a spring plate extending between and overlying said ports, said plate 55 normally closing said atmospheric port and being adapted to be flexed by the application of suction to gradually open said atmospheric port and close said crankcase port.

6. An engine having a crankcase having an air inlet, an air chamber provided with a suction port, a port connecting the crankcase and chamber, an atmospheric port leading 60 into the air chamber, and a suction operated valve in said chamber normally closing said

last named port and adapted upon application of suction to gradually open said atmospheric port and close said crankcase port.

7. An engine having a crankcase having an air inlet, an air chamber provided at one end with a suction connection, and at the other end with a port connecting the crankcase and chamber, an atmospheric port leading into the air chamber, and a suction operated valve in said chamber extending between and overlying said last named ports and adapted upon application of suction to gradually open said atmospheric port and close said crankcase port.

8. An internal combustion engine provided with a crankcase having an air inlet, a valve chamber in communication with the crankcase, an air chamber provided with a suction connection, a port connecting said chambers, said air chamber being provided with an atmospheric port, and means in said air chamber normally closing said atmospheric port and adapted upon application of suction to open said atmospheric port and close said crankcase port.

9. In combination with a pair of opposed ports, a flap valve extending between and overlying said ports and adapted to normally close one of said ports and to be swung into position to close the other of said ports, said other port having its seating end cut on a radius drawn from the axis of oscillation of the valve.

In testimony whereof I affix my signature.

RAGNAR CLASON.
